UNITED STATES PATENT OFFICE.

BENJAMIN LIPPER, OF PHILADELPHIA, PENNSYLVANIA.

DESIGN FOR BRAID.

SPECIFICATION forming part of Design No. 23,084, dated February 27, 1894.

Application filed January 26, 1894. Serial No. 498,150. Term of patent 3½ years.

To all whom it may concern:

Be it known that I, BENJAMIN LIPPER, a citizen of the United States, residing in Philadelphia, Pennsylvania, have invented a new 5 and original Design for Braid, of which the following is a specification.

My design is fully shown in the accompanying drawing which represents a strip of the trimming.

10 The design comprises the central openwork band *a* and edge bands *b*. The central band *a* comprises cross bars *d* with which is intertwined a series of sets of threads *f*. Each band *b* has a series of rows of raised surface 15 stitches or loops *g*, and beyond each band *b* is a looped edging *i*.

The essential features of the design are the bands *a* and *b* of the character shown.

I claim—

The design for a trimming substantially as 20 described and as shown in the accompanying drawing.

In testimony whereof I have signed my name to this specification in the presence of two subscribing witnesses.

BENJAMIN LIPPER.
